United States Patent

Des. 238,304
Patented Dec. 30, 1975

238,304

BINOCULAR

Alfred Hengst, Wetzlar-Dorlar, Heinrich Janke, Braunsfels, and Ernst Ruehl, Naunheim, Germany, assignors to Ernst Leitz GmbH

Filed Dec. 9, 1974, Ser. No. 530,655

Claims priority, application Germany June 21, 1974

Term of patent 14 years

Int. Cl. D16—06

U.S. Cl. D57—1 E

Fig. 6

FIG. 1 is a top front perspective of a binocular showing our new design;

FIG. 2 is a front perspective thereof in a folded position;

FIG. 3 is a rear perspective view as seen in an alternate position to that illustrated in FIG. 1;

FIG. 4 is a rear perspective of the binocular in a folded position;

FIG. 5 is a front perspective of the binocular shown in FIG. 3; and

FIG. 6 is a rear perspective of a modified embodiment of the binocular illustrated in FIGS. 1-5 inclusive.

We claim:

The ornamental design for a binocular, as shown and described.
